FENCE RAIL CLAMP

Abraham Pinson, Brooklyn, N.Y.

Application October 3, 1958, Serial No. 52,865

Term of patent 14 years

(Cl. D54—13)

Figure 1 is a perspective view of a fence rail clamp showing my new design. The pipes represented in broken lines are for the purpose of illustration only.

Figure 2 is a top plan view thereof;

Figure 3 is a side elevational view of one of the sections shown in Figures 1 and 2.

Figure 4 is an end elevational view thereof; and

Figure 5 is a cross-section taken along line 5—5 of Figure 3.

The dominant features of my design reside in the portions shown in full lines.

I claim:

The ornamental design for a fence rail clamp, substantially as shown and described.
